CLAIM

The ornamental design for a headband for headlamp, as shown and described.

DESCRIPTION

The file of this patent contains at least one drawing/photograph executed in color. Copies of this patent with color drawing(s)/photograph(s) will be provided by the Office upon request and payment of the necessary fee.

The FIGURE is a front elevational view of a headband for headlamp in a flattened state, showing the new design.

The broken lines depict portions of the headband for headlamp that form no part of the claimed design. The dot-dash chain lines depict boundaries of the claimed subject matter and form no part of the claimed design.

1 Claim, 1 Drawing Sheet
